UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

DUST-GUARD FOR CAR-WINDOWS.

1,126,883.

Specification of Letters Patent.

Patented Feb. 2, 1915.

Application filed July 12, 1911. Serial No. 638,204.

To all whom it may concern:

Be it known that I, HARRY H. SCHROYER, a citizen of the United States, and a resident of the city of Chicago, in the county of

5 Cook and State of Illinois, have invented certain new and useful Improvements in Dust-Guards for Car-Windows; and I do hereby declare that the following is a full, clear, and exact description of the same, 10 reference being had to the accompanying drawings, and to the numbers of reference marked thereon, which form a part of this specification.

Dust in considerable quantities is drawn 15 beneath car windows, especially when the car is in motion. Movement of the car seems to produce an inward pressure in some instances, which assists in carrying the dust inwardly beneath the window sash.

20 The object of this invention is to afford a dust guard which effectually seals the sash against the admission of dust between the same and sill, and which also acts to produce an outward draft from the bottom 25 of the sash.

It is also an object of the invention to afford a construction in which dust or dirt is prevented from accumulating upon the sill, and in which the dirt or dust as it falls, 30 is promptly removed by the draft occasioned by the movement of the car.

It is also an object of the invention to afford a construction which acts to wedgely engage the bottom of the sash to 35 spring the same inwardly into positive engagement with the sub-sill on the inner side of the frame, and also to utilize the draft occasioned by the movement of the vehicle to produce a direct outward draft from the 40 bottom of the sash to withdraw the dirt and dust therefrom.

The invention consists in the matters hereinafter described and more fully pointed out and defined in the appended claims.

45 In the drawings: Figure 1 is a fragmentary, horizontal section of a window equipped with a device embodying my invention, and showing the latter in top plan view and also in horizontal section. Fig. 2 is a vertical section taken through the sash and the guard. Fig. 3 is an enlarged inverted plan view of a portion of the dust guard. Fig. 4 is a section on line 4-4 of Fig. 3.

55 As shown in the drawings: 1, indicates

the sill of the window frame; 2, the sub or interior sill, against the outer upper edge of which the bottom rail 3, of the sash bears, as shown in Fig. 2.

4, indicates the parting strip or stop on 60 the inner side of the sash. The inner face of the sash bears, of course, at its side rails against the stop 4, and the inner face of the bottom rail bears against the upwardly projecting outer edge of the inner or sub-sill 2, 65 as shown in Fig. 2. As shown also, the outer face at the lower edge of the bottom rail 3 of the sash, is chamfered or beveled under to serve as a wedge member.

Secured on the sill 1, is the dust guard 70 embodying my invention. This, as shown, comprises a main plate 5, of metal or other suitable material having one side thereof turned or flanged over to afford a longitudinal rib 6, of double thickness to bear 75

against the bottom rail of the sash, as shown in Figs. 1 and 2. Rigidly secured on said plate or web 5, on the under side thereof, by riveting or any suitable means, are deflecting members. These, as shown, (though not 80

necessarily) are constructed of stamped or pressed metal and comprise a succession of duplicate units arranged at short intervals apart, and which, by their shape, serve to cause an outward flow of air from the sill. 85 In construction, said members comprise plates 7, arranged at an angle with each other, and, as shown, integral in pairs, and which are secured to the web 5, with the apex of the angle formed thereby directed 90 against the inturned edge of the plate, and consequently toward the bottom rail of the sash, and spaced a distance therefrom, dependent only upon the width of the rib or web 6 itself. Said angle plates are pro-

vided with inturned ends 8, and secured thereto and bearing against said inturned angular ends 8, is a concave plate 9, the ends of which extend beyond said angular ends and to the edge of the plate or web 5. 100 Said deflecting members are secured on said web at short (but equal) intervals apart to afford a relatively narrow space therebetween. The dust deflector is secured on the sill 1, with the plate 5, uppermost, as 105 shown in Figs. 2 and 4, and affording the top of the device.

The operation is as follows: When the window sash is closed, the outer face thereof engages against the rib or web 6, and acts 110

to force the bottom of the sash inwardly to seal the same against the outer edge of the sub or inner sill 2. This in itself tends to greatly reduce the amount of dust that can 5 find entrance into the car, inasmuch as it tends to prevent dust from passing into the car beneath the window, and, of course, most of the dust and dirt projected against the window by the wind or air movement 10 occasioned by the passage of the train, falls upon the plate 5, and thence is discharged therefrom outwardly. Should any portion of the dust, however, find its way beneath the plate 5 and 6, the air impinging on the 15 concave or curved plates 9, is deflected outwardly from the car by the curvature thereof, and in consequence, the air beneath said plate adjacent the sash is agitated and exhausted or is drawn outwardly. Of course, 20 this is assisted by the inclined sides of the deflector, inasmuch as the dust and dirt particles more readily slide, or are drawn down the inclined surface of the sill and are thence discharged into the narrow space be- 25 tween the adjacent ends of the deflector plates 9, and at a point where even a slight tendency to outward flow of the air beneath said plate, acts to discharge the dust and dirt therewith. Of course, should it be 30 desired to raise the window, no obstruction whatever is afforded by the dust guard. The window operates as easily as before the application of the guard. Of course, the deflector plates 9, may have any desired 35 curvature, and the deflecting units on said plate, may be of any desired size or number, and, of course, details of the construction may vary through a wide range, and I do not purpose limiting the patent to be issued 40 on this application otherwise than necessitated by the prior art, for I have shown but one (and that a preferred) form of the invention, and am aware that numerous details of construction may be varied without 45 departing from the principles of the invention.

I claim as my invention:

1. A dust guard for car windows, comprising a main plate adapted to contact with 50 the outer face of the window sash when the latter is closed, angle plates secured to the underside of said main plate and having

their converging ends disposed toward the window sash, and a deflecting member secured to the other ends of said angle plates. 55

2. A dust guard for car windows, comprising a plate having one edge thereof folded over to afford a longitudinal rib, angle plates secured thereon with the apex of the angle formed thereby directed toward 60 the rib on the first-mentioned plate, and a deflecting member secured to the ends of the angle plates opposite the apex.

3. A dust guard for car windows, comprising a main plate having one edge there- 65 of beaded over upon itself to provide a rib adapted to contact with the outer face of the window sash when the latter is closed, and a plurality of groups of members de- pending therefrom and each comprising 70 angled walls and a curved wall coacting with said angled walls to cause a flow of air toward the tips of said curved wall as the car moves.

4. A dust guard for car windows, comprising a flat main plate, an angle deflecting plate depending from the under surface of said main plate, and a curved wall joining the extremities of said angle plate and projecting beyond the same. 75

5. A dust guard for car windows, comprising a succession of triangular members secured on the sill in close relation with the bottom sash rail and with one vertex of each directed toward said rail, a concave side on 85 each triangular member opposite said vertex and acting as a deflector to exhaust the air from between said members, and a cover plate for said members having a projecting edge thereon acting to bear against the sash. 90

6. In a device of the class described, adapted to utilize a current of air flowing past one edge to cause a flow from the opposite edge thereto, comprising a flat plate, a plurality of depending plates converging 95 in pairs, and a curved plate joining the extremities of each pair of converging plates.

In testimony whereof I have hereunto subscribed my name in the presence of two sub-
scribing witnesses.

HARRY H. SCHROYER.
